UNITED STATES PATENT OFFICE.

CHARLES LEA, OF BOSTON, MASSACHUSETTS, ASSIGNOR TO THE AUTOMATIC MERCHANTIZER, INC., OF BOSTON, MASSACHUSETTS, A CORPORATION OF DELAWARE.

COIN-CONTROLLED APPARATUS.

Application filed August 28, 1920. Serial No. 406,619.

To all whom it may concern:

Be it known that I, CHARLES LEA, a citizen of the United States, and a resident of Boston, county of Suffolk and State of Massachusetts, have invented an Improvement in Coin-Controlled Apparatus, of which the following description, in connection with the accompanying drawings, is a specification, like characters on the drawings representing like parts.

My invention relates to coin controlled apparatus and particularly but not exclusively to vending machines.

My invention will be best understood from the accompanying drawings and description of a specific embodiment of my invention submitted for illustrative purposes, while its scope will be more particularly pointed out in the appended claims.

20 In the drawings:

Figure 1 shows a front elevation of my machine, parts being broken away;

Fig. 2 is a section on the line 2--2 of Fig. 1;

25 Figs. 3 and 4 are sections on the lines 3--3 and 4--4 of Fig. 2; and

Fig. 5 illustrates a detail.

Referring to the drawings, I have provided a suitable base 1 to which is secured a 30 hopper 2 for holding the articles to be vended, such articles being indicated in Fig. 1 by circles 3 representing cans. It will be understood however that my machine is not limited to cans and is adapted to vend other articles. In order that the contents of the 35 hopper may be rendered visible, I preferably form the same of wire mesh. Closing the hopper I provide a hinged cover 4 provided with a lock 5 to prevent unauthorized tampering with the contents.

40 Below the hopper I provide a casing 6 containing mechanism for discharging the cans. This casing is formed in two sections, each provided with an end wall 6' 45 and a peripheral wall 7. For securing the sections in assembled relation I provide the bolts 8.

50 Mounted in suitable bearings in the opposite end walls of the casing is a rotatable spindle 9 which provides a pivotal support for an article carrier 10 rigidly secured thereto. The article carrier comprises circular end plates 11 having the arcual cut-away portions providing the radial walls 12 55 and 13. Supported by the end plates is a

transverse sheet of material having the portions 14 conforming to the circular edges of the end plates and a receding portion 15 which together with the end plates forms a pocket 16 for receiving one of the cans. For 60 securing the sheet to the end plates I preferably form grooves 39' in the plates conforming to the edges of the sheet and after inserting the edges of the sheet, the parts are held in assembled relation by means of 65 bolts 40'.

When the carrier is in the position shown by Figs. 1 and 4, the can will drop into the pocket 16 and when the carrier is moved in a counter-clockwise direction to bring the 70 pocket opposite the opening 17 in the peripheral wall of the casing, the can will fall from the pocket and be caught by the platform 18 carried by the casing. For moving the carrier I provide a suitable lever 75 19 fixedly secured to the spindle 9. For retracting the carrier I provide a spring 20 adapted to hold normally the radial surfaces 12 of the end plates of the carrier against the pin 21 extending from opposite sides of 80 the casing and supported by the end walls thereof. For permitting the proper functioning of the spring I provide the end plate 11 adjacent the back of the casing with a suitable flange providing a cylindrical surface 22, about which the spring is adapted to wrap when the carrier is turned. This spring is secured to the carrier at one end 23 and at the other end to the pin 21, which also serves as a stop for limiting the motion 85 of the carrier when the radial surfaces 13 are moved into contact with it at the opposite end of the travel of the carrier.

I provide coin controlled mechanism for permitting the movement of the carrier from 90 its normal position to its discharging position. To this end I pivotally support by means of a pivot 24 carried by the front end plate a movable member in the form of a lever 25 having an upper surface 26 inclined 100 to the inner surface of the circumferential portion 7 of the casing. Connecting the lever and the casing is a spring 28 which tends to hold the lever in its raised position. On the end plates of the carrier adjacent the 105 lever I provide the spaced lugs 30 and 31 which coat with a detent 29 carried by the side of the lever adjacent the carrier. These lugs are provided with stop surfaces 36 and 37 adapted to lock with the surface 38 of 110

the detent and provided with surfaces 39 and 40 permitting the lugs to ride over the detent. The parts are so arranged to provide a space between the surface 38 of the 5 detent and the surface 36 of the lug sufficient to permit a limited initial movement of the carrier. The lug 31 I provide with a slot 32 into which a coin may be dropped when the carrier is in its coin receiving position 10 through a slot 33 formed through the wall of the casing. Insertion of a coin at other times is prevented by means of the upper surface of the lug 31 and the upper surface of the flange 34, contiguous therewith.

15 The operation of my device is as follows: After the coin indicated at 35 in Figs. 2 and 3 is dropped into the machine, the handle 17 is turned in the direction of the arrow shown in Figs. 1 and 3 and the lug 31 20 attached to the carrier moves the coin with diametrically opposite portions of its edge in contact with the inner surface of the peripheral wall of the casing and the surface 26 of the lever. As these surfaces are inclined towards each other, the initial movement permitted by the space between the adjacent portions of the detent and lug 30 suffices to cause the surfaces to be separated enough to cause the lever to be swung down- 25 wardly to move the stop 29 out of the path of the lugs 30 and 31, which permits the handle to move the article carrier to its discharging position. After the coin is moved past the end of the surface 26 of the lever it 30 falls to the bottom of the casing whence it may be removed through the door 38' provided with a suitable lock. After this, if the handle is released, the spring 20 will return the carrier to its coin receiving position, the 35 surfaces 39 and 40 of the lugs 30 and 31 riding over the detent. If the operator permits the carriage to return slowly, a cam will fall into the pocket of the carrier at a point intermediate the discharging and coin receiving positions and before the lug 30 moves past the detent, under which conditions, in the absence of the lug 31, the carrier could again be moved to its discharging position without the insertion of a coin. To prevent 40 this I provide the lug 31 with the stop surface 37 which is so positioned to cause it to be engaged by the detent in this intermediate position in which the carrier may be charged.

45 It will be noted that I have provided a locking mechanism permitting an initial movement of the carrier from its coin receiving position sufficient to disengage the lock to permit the carrier to be moved to its discharging position and that between these positions is afforded a charging position.

50 Although I have described one specific embodiment of my invention it is to be understood that I am not to be limited thereby to its specific details and arrangement of parts

and that extensive deviations from the same may be made without departing from the spirit of my invention.

Claims:

1. In a vending machine, an oscillatory 70 delivery member, a cylindrical casing for said member, a locking pawl pivoted to said casing and having an upper surface inclined to the surface of said casing, a part carried by said delivery member and engaged by 75 said locking pawl to normally prevent all but a slight movement of said delivery member, a lug carried by said delivery member and projecting between the cylindrical wall of said casing and said pawl, a coin slot in 80 said casing and an aligned coin slot in said lug extending therethrough, whereby when a coin is inserted through said coin slot it will enter said aligned slot and rest on said pawl with its edge opposite said pawl in position to slide along the cylindrical surface of said casing.

2. In a vending machine, a carrier having an initial position and mounted to move to a discharging position, a charging position intermediate the first mentioned positions, coin controlled locking mechanism arranged to enforce the movement of said carrier to the initial position preliminary to its movement to the discharging position, and said locking mechanism comprising a single pawl and a pair of spaced stop members cooperating with said pawl.

3. In a vending machine, a carrier having an initial position and mounted to move to a discharging position, a charging position intermediate the first mentioned positions, coin controlled locking mechanism adapted to receive a coin in the initial position, said locking mechanism being arranged 100 to enforce the movement of said carrier to the initial position preliminary to its movement to the discharging position, and said locking mechanism comprising a single pawl and a pair of spaced stop members 105 cooperating with said pawl.

4. In a vending machine, a carrier having a coin receiving position, a discharging position and a charging position intermediate the two first mentioned positions, and coin controlled locking means, including a single pawl and a plurality of cooperating stops for locking said carrier in its receiving position and for enforcing movement of the carrier to its coin receiving position preliminary to its movement to its discharging position.

5. In a vending machine, a carrier part having an initial position and mounted to move to a discharging position, a charging position intermediate the first mentioned positions, a casing part for said carrier, a movable member carried by one of said parts and having a surface inclined to a surface carried by the other, a coin receiving mem- 130

- ber having a coin receiving position and adapted to be moved by the operator to carry a coin with opposite sides in contact with said surfaces whereby to operate said 5 movable member, locking means operated by said movable member, said locking means having means enforcing the movement of said coin receiving member to its coin receiving position preliminary to movement 10 of the carrier to its discharging position.
6. In a vending machine, a carrier member having a coin receiving position, a discharge position and a charging position intermediate the two first mentioned positions, 15 a casing member, a movable member carried by one of the first named members, a plurality of means carried in spaced relation by the other of the first mentioned members and adapted to engage said movable member in such manner as to prevent movement toward the discharging position, one 20 of said means being adapted to automatically engage said movable member when the carrier is moved into charging position and the other when said carrier is moved into coin receiving position, coin controlled mechanism for operating said movable member to release said means, and means operative only 25 when the carrier is in coin receiving position to permit the positioning of a coin in said mechanism.
7. In a vending machine, an oscillatory shaft for operating the discharging mechanism of said machine, said mechanism having a coin receiving position, a discharging 30 position and a charging position intermediate the coin receiving and discharging positions, a pawl for locking the carrier, a pawl engaging stop for preventing movement toward the discharging position when the mechanism is in its coin receiving position, a second pawl engaging stop for preventing movement toward the discharging position when the mechanism is in its charging 35 position, and means effective only when the mechanism is in its coin receiving position for causing a coin to engage said pawl and release it.
8. In a vending machine, an oscillatory 40 discharging mechanism, a stationary member, a pivoted pawl, a part for engaging said pawl and normally preventing all but a slight movement of said discharging mechanism from its coin receiving position, a part constructed to hold a coin in position 45 to rest with its edge on said pawl and to slide over said stationary member whereby said slight movement will depress said pawl when a coin is inserted and release said mechanism, said mechanism being constructed to 50 have a charging position on its return movement, and said part which is constructed to hold the coin also being constructed to engage said pawl in said charging position.
9. In a machine for vending cans, a hopper for said cans and having an open end, a pivoted member having a recess constructed to receive a can when moved in alignment with said open end, a casing for said pivoted member, a pawl pivoted on said casing, a part on said pivoted member engaging said pawl, means for placing a coin on said pawl and forcing it to slide along said pawl in contact with said casing for moving the pawl out of engagement with said part, and 55 a second part on said pivoted member cooperating with said pawl for ensuring the insertion of a coin before said pivoted member can be moved to discharge a can.
10. In a machine for vending cans, a hopper for said cans and having an open end, a pivoted member having a recess constructed to receive a can when moved in alignment with said open end, a stationary member adjacent said pivoted member, a pawl pivoted on said casing, a part on said pivoted member engaging said pawl, means for placing a coin on said pawl and forcing it to slide along said pawl in contact with said stationary member for moving the pawl out 60 of engagement with said part, and a second part on said pivoted member cooperating with said pawl for ensuring the insertion of a coin before said pivoted member can be moved to discharge a can.
11. In a vending machine, an oscillatory delivery member, a cylindrical casing for said member, a locking pawl pivoted to said casing and having an upper surface inclined to the surface of said casing, a part 65 carried by said delivery member and engaged by said locking pawl to normally prevent all but a slight movement of said delivery member, a lug carried by said delivery member and projecting between the cylindrical wall of said casing and said pawl, said lug having a part for engaging said locking pawl when said delivery member is in an intermediate position of its stroke, a coin slot in said casing and an aligned coin slot in said lug extending therethrough, whereby when a coin is inserted through said coin slot it will enter said aligned slot and rest on said pawl with its edge opposite said pawl in position to slide 70 along the cylindrical surface of said casing.
- In testimony whereof, I have signed my name to this specification.

CHARLES LEA.
